UNITED STATES PATENT OFFICE.

FRANK L. NICHOLS, OF STAMFORD, CONNECTICUT, ASSIGNOR TO INTERNATIONAL MUNITIONS COMPANY, INC. OF DELAWARE.

MORTAR-BOMB.

1,309,743.

Specification of Letters Patent. Patented July 15, 1919.

Application filed July 5, 1918. Serial No. 243,430.

To all whom it may concern:

Be it known that I, FRANK L. NICHOLS, a citizen of the United States of America, residing at Stamford, in the county of Fairfield, State of Connecticut, have invented a new and useful Improvement in Mortar-Bombs, of which the following is a specification.

The invention relates specifically to a shell, or bomb, which has to do with a mortar, and is intended more particularly for ranges extending from 1800 to 2500 yards and it is provided with means for propelling it from the mortar with additional means for functioning the high explosive by a time fuse, or if preferred upon impact, that is to say, upon the arrival of the implement at its objective.

The invention is particularly adapted to, and is intended to be used in connection with, a mortar which is entirely closed at the breech, the missile being inserted at the muzzle by the operator and permitted to drop by gravity; the gun, or mortar being at an angle of 45 degrees; the missile, or the initiating element of its propelling unit, functions the instant it reaches the bottom of the bore, thus eliminating any trigger or other firing mechanism.

In other words, it is used in connection with a closed mortar having no breech mechanism and its firing and propelling unit is adapted to function automatically and start to leave the mortar absolutely at the instant it reaches the end of its inward travel.

It is, as before intimated, provided with fixed ammunition, one unit of said ammunition being devoted to the propelling charge, and the other unit of the ammunition being devoted to the bursting charge.

The shell, or bomb, is likewise particularly designed to be used in connection with a special form of mortar, which is the subject matter of another application filed concurrently herewith and serially numbered 243431, said mortar having a major and minor bore with a tapered connecting wall; the shell or bomb, herein shown, described and claimed is also partly described in the aforesaid application, but it is fully described and claimed herein.

The shell, or bomb, is provided with an annular gas check which as the missile is proceeding from the muzzle to the breech of the bore remains quiescent, but immedi-

ately upon the return trip outwardly it flares laterally and seals the air passage around the shell and compels the latter to assume the entire blow of the explosive; these operations, and the means I have devised to carry them into effect, complete the main part of my present invention.

In carrying my invention into effect, I employ for my propelling charge a paper shell cartridge of the commercial type and I load it with a high grade of smokeless powder, and I so place and arrange it in connection with the shell, that when the latter leaves the mortar, it carries the cartridge shell with it thus cleaning the gun automatically in every instance.

Also in carrying my invention into effect, I employ the explosion from the propelling charge to ignite the time fuse of the fragmentizing or bursting charge, thus making a continuous and automatic arrangement.

For the purpose of more specifically explaining my invention, I will describe it in connection with the accompanying drawings, which form a part of this specification and in which

Figure 1—represents a longitudinal section of the inner end of a gun or what I will refer to herein as my improved mortar showing the shell or bomb in position therein, and about to function; this view is on line I—I Fig. 3.

Fig. 2— is a similar detail view immediately after the functioning act and showing on the line II—II Fig. 3.

Fig. 3— is a cross section on the line III—III of Fig. 1 looking in the direction of the arrow.

Fig. 4— is a detail view of the gas check hereinafter described.

In order to explain my invention in the simplest way, I will proceed to first describe the mortar which represents the preferable form of gun to employ it with; that is to achieve the best results and more particularly to secure the longest range with a minimum weight of gun and appurtenances.

At 10 I show a gun barrel and at 11 a breech reinforce; 12 is a breech base having an exterior screw thread 13 which intermeshes with complementary screw portions 14 on the gun barrel and reinforce, locking and securing all these parts together in a simple manner.

At 15 is a supplementary inserted barrel

2
provided with a tapering portion 16: in this manner the mortar is provided with three dimensioned bores; a major bore, or the bore of the barrel 10; a minor bore or the bore of the insert tube 15 and a slanting bore consisting of the tapered portion 16, extending between and connecting the major and minor bores.

The body of the projectile containing the high explosive is shown at 17; it has a suitable filler plug 18: extending from the base of the shell proper is a tube 19 formed integrally therewith. This tube constitutes the receptacle for the expelling unit, which latter consists of a commercial cartridge, the tube being of a size and shape to take it snugly. This cartridge is provided with a suitable explosive and expelling charge and consists of a container formed of paper sides 20, a metal base 21 and it is furnished with a primer 22. The tube 19 being opened at the bottom, the cartridge is inserted therein and for transportation and loading purposes is retained in position by the spring catch 23.

25 The tube 19 is provided with recesses or portals 24 preferably four in number. They are openings in the walls of the tube 19, and they open out into the explosive chamber 25 formed between the walls of the tube 19 and the bore of the mortar. This chamber provides the necessary space for the expansion of the gases.

At 26 is shown a primer striking pin. As the projectile descends the blow resulting from the impact of the implement causes the requisite penetration and initiates the firing operation of the expelling unit.

At 27 I show the annular band positioned around and recessed in the base of the shell 40 17. At 28 is a locking ring, see Fig. 2, which holds the band at its outer edge; when the band receives the blow and pressure from the gases, as will be explained, the band will be pressed outwardly against the bore turning on the outer edge which will be held by the ring 28: as will be seen, the band 27 is positioned in a suitable inset or cut away portion at the base of the shell proper, peripheral channels 29 being provided to 50 distribute the gases evenly around and inside the band and avenues 30 extending to the explosive chamber 25 to facilitate the movement of said gases to the channels 29.

At 31 are radially extending guides 55 formed in the shell body 17 to keep the missile to a central position in the bore; 32 are wings formed on the exterior of the extension 19; they provide wings for the missile in flight and at their lower ends as 60 shown at 33, they are extended laterally to come against the walls of the minor bore.

At 34 is shown the metal head of the expelling charge container and at 35 is an annular shoulder on the interior of the extension 19 which snugly receives and cen-

ters the outer end of the explosive container, that is to say, the paper cartridge, the said paper cartridge being adapted to move up and over the slanting surface 36 to reach the shoulder 35. It will be seen also that I provide spaces 37 between the wall of the paper shell and the wall of the extension 19; this facilitates the breaking of the paper shell wall when the expelling charge functions; the wad or closing member of the cartridge 70 is shown at 38 and a penetrating plug having a point 39, said plug 40 being screw threaded at 41 into the base of the high explosive shell and having an entrance 42 providing an avenue to any suitable fuse 43 and 80 firing unit for the high explosive; this phase of the construction, I will not go into as any assemblage and arrangement of parts may be employed, and in fact, though I have shown a time unit, I may if preferred introduce an impact proposition of any approved and available form.

By referring to Fig. 1, the projectile has just reached the end of its downward descent and the striking point 26 is entering the primer 22 to function: in Fig. 2, the parts are shown after the functioning, the projectile is leaving the mortar and the paper and metal walls of the cartridge having been broken, mutilated and distended laterally 95; are locked in the walls of the extension 19; a pocket or ledge 44 being further provided if desired to emphasize this situation.

From the foregoing it will be seen that I have shown and described an implement 100 which embraces means for providing a rapid and unimpeded descent of the projectile in the mortar from the muzzle to the breech by means of a peripheral channel and means for functioning the expelling charge by impact 105 of the projectile in the breech of the mortar.

Secondly, I have shown a means for instantly effecting a closure of this channel upon, and by, the functioning of the expelling charge and before the inertia of the 110 shell is overcome, this closure being effected by an expandible member: specifically a metal band surrounding the base of the shell which moves over to, against, and all around, the bore of the mortar: this constitutes a gas check and effectually imprisons and utilizes all of the explosive and expanding gases.

Thirdly, I have also shown that this expandible band follows up and registers 120 against the successively enlarged bores of the mortar and instantly and automatically adjusts itself thereto as it moves outwardly through the mortar, thus maintaining the gas check intact and unimpaired at all 125 times.

Fourthly, I have disclosed means for positioning fixed ammunition both as to the expelling charge, as well as to the high explosive, and have provided a connection 130

from one to the other, functioning the initiating element of the chain from the gravity blow of the expelling charge in the base of the mortar.

5. Fifthly, I have also shown a projectile provided with a high explosive envelop of slightly less diameter than the major bore with radially extending guides formed integrally therewith and co-extensive with 10 said major bore.

6. Sixthly, I have also shown that the main body of the projectile is formed with an integral inner extension of less diameter providing a receptacle for the expelling unit, 15 an annular chamber surrounding it for the explosive gases, wings on its sides for guidance, portals to permit the lateral functioning of the explosive container, together with means for locking the explosive container 20 to the projectile.

Having thus described my invention, the following is what I claim as new and useful therein and desire to secure by Letters Patent:—

25. 1. In a projectile, means for providing a peripheral channel during its descent into its mortar from the muzzle, and means for instantly effecting a closure of this channel upon and by, the functioning of an expelling charge.

2. A projectile having means for avoiding an air cushion in its descent into the mortar from the muzzle in combination with an expandible member providing a gas check.

3. In a projectile, means for avoiding an air cushion in its descent into the mortar from the muzzle, and means for providing a gas check upon the functioning of the expelling charge.

40. 4. In a projectile, means for avoiding an air cushion in its descent into the mortar from the muzzle, an annular expandible member positioned on its periphery and means for forcing the member against the several bores by the functioning of the expelling charge.

45. 5. The combination in a projectile, of a main body having a diameter smaller than its coördinating mortar bore and radially

extending guides of the same diameter as 50 said mortar bore.

6. In a projectile, the combination of a main body, a tube of smaller diameter providing a receptacle for the expelling unit, and wings formed upon the exterior of the 55 tube for guiding the projectile.

7. In a projectile, the combination of a main body, a rearwardly extending tube providing a receptacle for the expelling charge container, and means in said tube for 60 locking the charge container to the tube and insuring its departure therein when the expelling charge functions.

8. In a projectile, the combination of a main body, an expelling charge, a container 65 for said charge formed of paper and metal, and means whereby when the charge functions the container breaks and becomes interlocked with the projectile.

9. The combination with a projectile, of 70 an expelling charge, a container therefor and means for locking the container to the projectile after the ignition of the charge, but before the inertia of the projectile has been overcome.

75. 10. The combination, in a muzzle loading projectile, of a shell body, an impact expelling unit, a gas check retained in an inoperative position during the inward travel of the shell, and means, operating at the 80 start of the outward travel of the shell, for forcing the gas check into operative position.

11. The combination, in a projectile, of a shell body, an expelling charge, means for securing the expelling charge in the projectile and means for functioning the charge 85 and expelling both the projectile and the charge securing means upon a gravity blow of the projectile at the base of its coördinating mortar bore.

90. 12. The combination in a projectile, of a shell body, an expelling charge, a container therefor, and means for functioning the charge and expelling the projectile and container upon a gravity blow of the projectile 95 at the base of its coördinating mortar bore.

FRANK L. NICHOLS.
